UNITED STATES PATENT OFFICE.

JAMES W. KNOBLOCK, OF ELMIRA, NEW YORK, ASSIGNOR TO AMERICAN LA FRANCE FIRE ENGINE CO., INC., OF ELMIRA, NEW YORK, A CORPORATION OF NEW YORK.

RESPIRATOR.

1,410,928.

Specification of Letters Patent. Patented Mar. 28, 1922.

Application filed May 22, 1920. Serial No. 383,549.

To all whom it may concern:

Be it known that I, JAMES W. KNOBLOCK, a citizen of the United States, residing at Elmira, county of Chemung, and State of New York, have invented certain new and useful Improvements in Respirators, of which the following is a specification.

The present invention relates to improvements in the type of respirators for filtering 10 dusts and light fumes from air of the type in which the filtering medium is a damped sponge or a filtering paper. The main purpose of the present invention is to produce a more efficient respirator of the type referred to, by providing an extra large filter 15 area that will produce efficient filtration with the least breathing resistance, and a device in which the dead air or rebreathing space inside the respirator is reduced to the least 20 possible percentage of a normal breath.

In accomplishing these results the respirator of the present application comprises a cup shaped metal body, carefully designed to conform to the contour of the human face 25 and having a soft rubber air cushion, which assures a tight fit with least possible pressure on the face, and a relatively large filter box, containing either a sponge or paper filter material, and freely communicating with the 30 respirator body through a large opening. The filter box is formed preferably by a flattened cylindrical container having a circular opening formed in its rear wall and the metal surrounding this opening turned 35 over or flanged into a similar opening in the front wall of the respirator body. By this means the respirator body and filter box are permanently secured together. The attachment of these two parts is made more rigid 40 by means of rivets passing through their adjacent walls near said communicating opening. The filter box is so arranged with reference to the respirator body that a pocket or trap is formed in the filter box below the 45 opening communicating with the respirator body, so that any excess moisture collecting upon the filter sponge or paper from the breath of the wearer will gravitate to the bottom of the filter box and be kept out of 50 the respirator body and away from the face of the wearer.

In order that the invention may be more fully understood it will first be described with reference to the accompanying draw-

ings and afterward pointed out more particularly in the annexed claim.

In said drawings:

Fig. 1 is a side elevation of the improved respirator, indicating by dotted lines the position of the wearer's head in the respirator, and also showing in dotted lines a flexible respirator hood that can be worn with the respirator.

Fig. 2 is an external front view of the respirator.

Fig. 3 is a vertical longitudinal sectional view of the same taken on the line 3—3 of Fig. 4.

Fig. 4 is a transverse sectional view taken on the line 4—4 of Fig. 3.

Fig. 5 is a view similar to Fig. 3 of a slightly modified form showing the use of the paper filter.

Fig. 6 is a view similar to Fig. 2 of the paper filter form of respirator.

The improved respirator is formed with a respirator body 1 of metal, preferably such as aluminum, carefully designed to fit over the mouth and nose of the wearer. This cup shaped metal body 1 is conformed 80 as closely as possible to the contour of the face so as to reduce to a minimum the free space between the respirator body and the wearer when it is in use.

The shaped edge of the body 1 has 85 mounted upon it, in the usual manner, an inflatable soft rubber cushion 5, which fits tightly against the face of the wearer without undue pressure. The air cushion can be inflated more or less to accurately adjust 90 itself to different profiles. An elastic band indicated at 10 is riveted at 11 to the respirator body in position to be passed around the head of the wearer, and provided with a fastening buckle or a similar device for 95 adjustably securing it in place.

In Figures 1, 2, 3 and 4, 15 is a circular cup or box formed with a central opening 16, having the metal of its back wall passed through a similar opening formed in front 100 of the respirator body 1 and turned over or upset therein for permanently securing the box 15 to the body portion 1. This attachment is made more secure by means of a rivet 17 passed through the adjacent walls 105 of respirator body 1 and filter box 15, said rivet holding the parts against relative motion. A felt washer or ring of packing

material 19 is confined between the filter box and respirator body. The box 15 is designed to support a filter sponge 20 which is engaged upon its outer surface by a circular sheet of metal gauze 21, held in place by a flanged cover ring 22, which is attached to the filter box by any suitable means.

It will be observed that the filter box presents a relatively large filtering area, 10 and that the opening from the filter box to the respirator body is a large unrestricted passage for the free movement of air caused by the breathing of the wearer. The lower portion of the box presents a trap to collect 15 any excess moisture from the moistened filtering sponge, particularly from the accumulation of moisture from the breath of the wearer. This arrangement prevents moisture from entering the respirator body 20 proper and keeps it away from the face of the wearer.

As shown in Fig. 1, the improved respirator may be combined with any of the well known forms of cloth respirator hoods, 25 such as indicated by dotted lines 25.

In Figs. 5 and 6, the improved respirator is shown with a slightly modified form of filter box. The main difference in this form from the sponge type of respirator 30 just described, is the provision of a somewhat flatter filter box 30 of relatively larger diameter, arranged to receive several layers of filter paper indicated at 31. A strip of wire gauze 32 is slightly arched over the 35 opening 33 leading to the respirator body 1, to hold the filter paper away from said opening to increase the available filtering surface and improve the freedom of the circulation of air. The filter box 30 is 40 cured to the respirator body 1 in the same manner as above explained, excepting there

are two rivets 34 passing through the walls of the respirator body and filter box. The layers of filter paper are retained in the filter box 30 by means of a sheet of wire 45 gauze 35, a flanged retaining ring 36 and some form of securing device, such for example as the detachable spring clasp indicated at 37.

With the improved respirator above described, whether of the sponge or paper filter type, the dead air or rebreathing space inside the respirator body contains less than 4% of a normal breath, and the extra large filter area assures efficient filtration with the least possible breathing resistance. No valves are necessary and there are no working parts to get out of order because of these two important features. The moisture trap in the filter box adds to the efficiency and comfort of the respirator.

I claim:

A respirator comprising a cupped respirator body designed to conform approximately to the contour of the human face 65 and cover the mouth and nose, said body being formed with an air inlet opening in its front wall, a circular filter box having an air opening centrally of its rear wall, a flange formed integrally with the rear wall 70 of said filter box and surrounding the air opening therein, said flange being adapted to be projected through the air inlet opening of the respirator body and bent back against said respirator body for securing 75 said filter box thereto, said air openings being in free communication, thereby forming a baffle and trap to exclude moisture from the respirator body, a filter material in said filter box and means for attaching 80 the respirator to the wearer.

JAMES W. KNOBLOCK.
